SPHYGMOMANOMETER

Erich Kallmeyer, Berlin-Grunewald, Germany

Application September 2, 1955, Serial No. 37,772

Term of patent 14 years

(Cl. D83—1)

Fig. 1 is a side elevational view of a sphygmomanometer showing my new design, the opposite side being substantially the same; and

Fig. 2 is a front perspective view thereof.

I claim:

The ornamental design for a sphygmomanometer, as shown and described.
